(57) **CLAIM**

The ornamental design for a golf tee tether, as shown and described.

DESCRIPTION

FIG. 1 is a perspective view of a golf tee tether attached to two golf tees shown in broken lines;

FIG. 2 is a top plan view with the loops being shown in an alternate position;

FIG. 3 is a side elevation view of FIG. 2; and,

FIG. 4 is an end view of FIG. 2.

The broken line showing the golf tees, golf ball and ground line forms no part of the claimed design.
